UNITED STATES PATENT OFFICE.

MATTHEW MORTON AND HENRY E. MORTON, OF MUSKEGON HEIGHTS, MICHIGAN.

SHAPER.

SPECIFICATION forming part of Letters Patent No. 682,218, dated September 10, 1901.

Application filed August 10, 1899. Serial No. 726,733. (No model.)

To all whom it may concern:

Be it known that we, MATTHEW MORTON and HENRY E. MORTON, citizens of the United States, residing at Muskegon Heights, county 5 of Muskegon, State of Michigan, have invented a certain new and useful Improvement in Shapers; and we declare the following to be a full, clear, and exact description of the invention, such as will enable others 10 skilled in the art to which it pertains to make and use the same, reference being had to the accompanying drawings, which form a part of this specification.

This invention relates to metal planing and 15 milling machines, and has for its object an improved machine having the characteristic feature of a draw-cut traveling-head shaper.

The machine embodying the invention consists of a large bed-plate provided with T-slots 20 by which the work may be secured during the action of the shaper. To this large bed-plate or base is detachably secured the main bed of the shaper itself in such a way that said shaper-bed may be detached from 25 said large bed-plate and moved to and secured in any other desired place upon said large bed-plate, or two or more shapers may be secured upon said large bed-plate by securing their beds to said large bed-plate, so that 30 large castings may be shaped in two or more places at once, and thus the necessity of moving the casting obviated. The shaper proper consists of its own bed, a column which is arranged to travel horizontally on the bed of 35 the shaper, a saddle arranged to travel vertically on the column, and the shaper-bar or ram carried by and arranged to travel horizontally through the saddle. By the employment of the vertical traveling saddle the machine 40 is adapted to be used on large work—that is, work that sets up high from the holding-bed or surface bed-plate upon which the work rests. The special construction of the ram and the tool-head attached to it enables 45 the machine to be used both on external and internal work, and it is adapted to do such diverse work as the cutting of key-seats in the taper end of propeller-shafts, the planing of cross-sections or engine-beds, pillow-blocks, anvil-blocks, and a great variety of 50 other irregular work which is beyond the

range of any machine commonly in use. For example, it can be employed to plane out the cavity or journal-bearing of a large trunnion, which is work of a character similar to that 55 done on a turning-lathe, although, because of its size and external shape, a trunnion-block cannot be turned, but must be planed by some machine to do irregular work.

An important feature of the machine embodying this invention is that it can be easily detached from the surface or foundation plate and used as a portable traveling-head shaper.

In the drawings, Figure 1 is a front elevation of the machine. Fig. 2 is an elevation of the right side of the machine. Fig. 3 is an elevation of the left side. Fig. 4 is a rear elevation. Fig. 5 is a plan view. Fig. 6 is a horizontal section through a part of the base of the machine, taken on the line $x-x$, Fig. 1, a part of the front of the machine being broken away. Fig. 7 is an elevation of a part of the base of the machine, a portion being broken away to show the interior construction. Fig. 8 is a vertical section on the line $y-y$, Fig. 4, looking from the left of said figure. Fig. 9 is a detail of a portion of the feed mechanism. Fig. 10 is a detail of the feed-regulating mechanism. Figs. 11, 12, 80 and 13 are details of the reversing mechanism. Fig. 14 is a longitudinal elevation of the driving mechanism of the milling attachment. Fig. 15 is a cross-section of the ram, showing the interior milling-journal. Fig. 85 16 is a detail of the frictional feed mechanisms. Fig. 17 shows a gage which indicates the rate at which the feed mechanism to the milling device is set to feed. Fig. 18 is a diagram representing the chain of gearing which 90 drives the ram. Fig. 19 is a diagram representing the gear for reversing the ram. Fig. 20 is a diagram showing the arrangement of gear which produces the slow vertical feed and the chain of gear which produces the 95 horizontal feed. Fig. 21 is a diagram showing the gear employed when a milling attachment is mounted on the front end of the ram. Fig. 22 indicates the action in working large pieces.

The machine is one in which a very heavy column is supported on a base on which the

column moves in one direction. The column itself carries a heavy saddle which is arranged to have vertical movement along the column, and the saddle carries a ram that has motion 5 at right angles to the motion of the column on the base, so that the resultant motion is universal—that is, the tool is moved from side to side by moving the column on the base, from front to rear by moving the ram 10 through the saddle, and up and down by moving the saddle on the column. The weight of all the mechanism is supported by the column, and in order that the moving of this may be easily effected the weight is partially supported on friction-rollers or traveling wheels. In order that the saddle may move easily on its vertical track, it is counterweighted. In each case, of course, enough of the weight of the machine bears on the 15 bed or on the rails of the vertical track to insure stability of the parts during the period of work.

The action of each part of the machine will be taken up by itself, as it is thought this 20 will make the understanding of the entire machine more clear.

The parts of the machine will be taken up in the following order: first, the ram actuating and reversing mechanism; second, the 25 milling mechanism; third, apparatus for facilitating the movements of the parts actuated by the feeding devices, and, fourth, the feeding devices.

The mechanism is not specially complicated 30 in any part, but because there is mechanism for each one of the three movements there are necessarily many parts, and the assembled machine consequently appears complicated.

40 The motion of the ram through the saddle.—The ram is a heavy bar 2^a, provided with rack-teeth 5^a on one of its vertical sides, and these mesh with rack-wheels 5^b, that are mounted in a casing that forms part of the saddle 2. The rack-wheels 5^b are on a vertical shaft, and the shaft is provided with a worm-wheel 5^c, that meshes with a worm on the shaft 5^d. This driving-shaft 5^d is carried by the saddle 2 and carries both a direct driving-wheel 15^e and a reverse driving-wheel 5^e. Both the wheels 15^e and 5^e belt to wheels on a counter-shaft 5^f, the one being belted directly and the other being belted by a cross-belt, and clutch arrangements are made to 45 throw the wheel 15^e into action and the wheel 5^e out of action or to throw the wheel 15^e out of action and the wheel 5^e into action, as may be desired, and a clutch-shift is used, which will be described hereinafter, which 50 automatically shifts the clutch at the end of the travel of the ram in either direction. The counter-shaft 5^f is driven from a motor W, that is carried on a bracket m, attached to the column C, and provision is made by passing 55 the belt from the motor over a fixed sheave 2^d on a bracket 2^e, carried by a post 2^b, thence over a traveling wheel 3^e, to permit of the ver-

tical travel of the saddle. The motor is especially useful when the shaper is employed as a portable tool or machine; but the machine 70 can be arranged so that it will receive motion from a separate source of power. The fixed sheave 2^d is provided with a take-up or belt-stretcher, which consists of a lever 3^d, fulcrumed on a bracket 2^e and which carries the 75 journal-bearing for the sheave 2^d at its free end. The other end is controlled by a spring 4^d, arranged to strain the belt passing around the sheave 2^d. The bracket 2^e is itself adjustable along the post 2^b and is held in its 80 adjusted position by set-screws 6^d. When the ram 2^a reaches the limit of its motion in either direction, an automatic reverse-gear unclutches one of the driving-wheels 5^e or 15^e and clutches the other one. This reverse-gear is arranged to be actuated automatically, and it is also arranged so that it may be actuated manually from several places. The automatic mechanism will be best understood from an examination of the diagram 85 Fig. 19, and Figs. 4, 11, 12, and 13. The clutches 4^e and 6^e are the ordinary clutches, sliding on the wheel-shaft and arranged to be engaged or disengaged from a wheel that is loose on the shaft when not in engagement 90 with the clutch. Any well-known clutch may be used, and it is not thought necessary to describe a specific form. The preferable form would usually be the clutch known as a "cone-clutch." The clutches are shifted by a sliding bar 7^e, that is mounted in sleeve-bearings 8^e and is arranged to slide parallel with the shaft 5^d. The sliding bar 7^e carries arms 9^e, that engage in grooves on the cone-sleeves of the clutches 4^e and 6^e. Midway between 95 the ends of the bar 7^e a lever 10^e (see Figs. 11, 12, and 4 and dotted lines in Fig. 5) engages with the bar, and this lever has a reciprocating motion along the axis of the bar 7^e and in the reciprocating motion carries the 100 bar 7^e with it. The lever 10^e is pivoted at its end on a pin, Figs. 11 and 12, and is provided on its upper side with an actuating-pin 12^e, on which there is journaled a friction-roller. Above the lever 10^e and in a parallel 105 plane thereto is a sliding plate 13, on the lower side of which is an irregular slot extending in a direction which is slightly slanting with reference to the direction of motion of the plate 13, Fig. 13. The walls of said slot engage the roller of the pin 12^e. When the plate 13 is reciprocated in the direction of its length, the pin 12^e is forced by the walls of said slot to reciprocate in a lateral direction with reference to said plate, and the lever 10^e is thereby oscillated about the pin 11^e. On the upper side of the plate 13 is a short rack 13^e, Figs. 2, 4, and 5 and dotted lines in Fig. 13, that engages a rack-wheel 14, and the rack-wheel is on a shaft 14^e, on which there is a 110 crank 15, Figs. 2, 3, 4, 5, and 11. From the crank a pitman 15^a (shown most distinctly by Figs. 3, 5, and 19) is connected through intermediate rock-shaft 16, rock-arms 16^e, and

link 16^f with the reverse-disk p. (Shown most distinctly by Figs. 2, 3, 4, 5, and 19.) Upon the same shaft with the wheels 5^b which reciprocates the ram 2^a is a spiral gear-wheel 5 which meshes with a similar gear-wheel upon a shaft P, Fig. 3, upon which last-named shaft is a disk p. Pivoted upon the shaft P is a lever q, Fig. 2, provided with a handle q' at its lower end and having one end of the link 16^f 10 pivoted to its upper end. Q is a lever pivoted to the saddle 2, provided with a handle at its upper end and having its lower end connected by a connecting-rod with the upper end of the lever q. On each side of the disk p is a tappet t t', arranged to be adjustable through a lug on said disk. Said tappets actuate the lever q, which lever is connected with the sliding bar 7^e by links 16^f, 15 rock-arms 16^e, rock-shaft 16, pitman 15^a, 20 crank 15, shaft 14^e, rack-wheel 14, rack 13^e, plate 13, pin 12^e, and lever 10^e. It will be seen that a movement of the lever q reverses the motion of the ram 2^a and that said lever may be actuated by hand by means of the 25 lever Q or by grasping the handle q'. Thus the ram may be reversed at any part of its stroke by hand and is automatically reversed at the end of its stroke by the mechanism described.

30 The milling attachment is a milling cutter-head arranged to be attached to an arbor that extends lengthwise through the ram, Figs 14 and 15. The milling-head itself is not shown, as it does not differ from those in 35 ordinary use. The arrangement for operating the milling-head is shown in detail in Fig. 14. (Compare Figs. 2, 3, 4, and 5.)

Parallel with the ram is a spline-shaft 21^a, actuated by bevel-gear 21^b and 21^c from the 40 driving-wheel 21^d. The driving-wheel 21^d receives its source of power from a cone-wheel 21^e on the main driving-shaft of the machine. The spline-shaft 21^a slides through a gear journaled to the side of the ram, and 45 the gear through two interposed wheels or pinions actuates the arbor in the ram.

The saddle 2 is fed vertically by means of a lead-screw E, Fig. 2, journaled upon the column C, and said column is fed horizontally 50 by a lead-screw G, Figs. 2 and 5, actuated by a pair of miter-gears, one of which is actuated by the spline-shaft F, Fig. 2, which shaft is actuated by a gear upon the saddle. The vertical movement of the saddle is made easy by a 55 counterbalancing-weight. In order to facilitate the horizontal motion of the saddle, carrying column C, the weight is taken off from the flat rails or bearings 20^a of the main base. The bearing of the column-base 20 on the flat 60 rails is the bearing which gives stability to the column during its period of work; but in order to relieve or lighten the bearing of the column on the rail 20^a a carriage 20^b, Figs. 6, 7, and 8, is placed under the bottom of the 65 column and receives a portion of the weight, and there is interposed between the truck-rail 20^c of the carriage 20^b and the column

one or a number of springs that lift the column with respect to the bearing-rail 20^a, and thus transfer part of the weight from the 70 bearings to the truck, so that an easy movement of one part over the other is secured. The tension of the spring is adjusted by the adjusting-screw 20^e. The column-base is secured to the main base by the ordinary dovetail overhang 20^f and gibbs 20^g. It will be readily seen that the weight of the column and other movable mechanism above the bed, which in machines as now made weigh over five tons, could not be successfully fed or 80 moved along on said bed without extremely expensive and powerful mechanism to give it an intermittent feed, varying between nothing and one-quarter inch at each stroke of the ram. With this truck carrying the quarter 85 portion of the weight of the machine a very simple friction device feeds with ease and the power is not much more than an ordinary thirty-six-inch swing-engine lathe requires.

When an ordinary cutting-tool is used with 90 the reciprocating ram 2^a, the machine requires an intermittent feed. When a milling-tool is used, a continuous feed is required. In order that the feed may be adapted to the above and other requirements of 95 practice, we employ two parallel shafts H and H', bearing in the saddle 2. The shaft H actuates a nut surrounding the lead-screw E, through which the vertical feed of the saddle is attained, and the shaft H' actuates a nut 100 surrounding the spline-shaft F, through which the horizontal feed of the column is attained. Above the shafts H H' is a shaft 30^e, which is actuated by a continuous friction-feed, and below said shafts is a shaft n, 105 actuated by an intermittent frictional feed. By gearing one of the shafts H H' to the shaft 30^e a continuous feed is attained. By gearing one of said shafts with the shaft n an intermittent feed is attained. 110

The frictional feed-actuating devices are described as follows: The intermittent feed of the machine is regulated by the friction-disk K, which engages in a ring 3^b and actuates by means of said ring an adjustable 115 wrist-pin 3. The wrist-pin 3 is a projection from a traveling nut that engages in guides on a plate which is made fast to a split ring 3^b, and the nut is capable of adjustment across the face of the plate, and such adjustment changes its eccentricity to the shaft of the friction-disk K. On the vertical shaft of the wheels which drive the ram is mounted a miter-gear that engages with a miter-gear on the horizontal shaft L. On the shaft L is 120 mounted the friction-disk K. Said disk engages in a split ring 3^b. At the opening of the split ring there are lugs 3^c, Fig. 10, and between the lugs a toggle-joint of two links 3^d and 3^e. The links of the toggle-joint are arranged to spread the split ring when pressed inward toward the center of the ring, and they are arranged to be pressed in by a cam or rectangular tappet-lever 3^f, which is hung on a 125 130

pin 4^t, which hinges it to the face-plate. The face-plate itself is secured to the ring by bolts 3^v. A stationary contact-arm or stop-arm 3^g extends across the axis of the friction-wheel and is provided at each end with limit-pins 3^t. The friction-wheel revolves with the shaft L, and it carries with it the friction-ring and the projecting face-plate and the wrist-pin 3 until the tappet-lever 3^t 5 strikes the limit-pin 3^h. When this occurs, the ring opens and no longer continues to revolve with the friction-disk, and consequently ceases to actuate the sector K'. The sector K' is hung on the saddle-frame and is 10 actuated by the wrist-pin 3, which engages in the slot k' in the arm k of the sector. The sector actuates a feed-rack-driving wheel M, and the feed-rack M', driven by wheel M, actuates a feed-wheel N, which is normally 15 loose on shaft n, but is caught by a dog O to the shaft, so as to cause the shaft n to revolve in either direction with the wheel; but when the wheel is caught to the shaft, so that it and the shaft revolve together in one direction, it is free to revolve without the shaft 20 in the reverse direction. The dog may be thrown to engage the wheel to the shaft, so that it will run loose either when the rack is traveling to the right or to the left. If it 25 runs loose with the rack traveling to the right, then it engages when the rack travels to the left. If it runs loose when the rack travels to the left, then it engages when the rack travels to the right—that is, the feed 30 may be regulated at will to take effect when the ram advances or when the ram retreats. The wheel N is arranged to mesh with a wheel on either the shaft H or a wheel on the shaft H'. The two wheels are interchangeable, but 35 are not of the same size, and one of them is entirely idle during operations of the shaper, in which the vertical and horizontal movement of the column are employed for feed purposes simply. The active wheel is placed 40 on the shaft H' when it is desired to give to the ram a horizontal motion across the base-plate. The active wheel then meshes with the wheel N and actuates the shaft H', and by 45 means of a beveled gear splined to the vertical shaft F it actuates the vertical shaft F, and motion is transmitted through this vertical shaft to a traveling nut on the horizontal feed-screw G. If vertical motion is desired, the active wheel is shifted to the shaft 50 H, and motion is transmitted through the shaft H to a traveling nut on the screw feed-shaft E. An elevation showing these shafts and gear-wheels is shown in Fig. 9, and, as 55 shown in that figure, the wheels N and the active wheel on the shaft H' appear in the same vertical plane. The larger inactive wheel on the shaft H appears in a plane behind that in which the wheel N is, and practically the larger wheel can never pass back 60 into engagement with the wheel N, on whichever of the two shafts it be placed, and it might be taken off and laid aside during the 65

time that the vertical or horizontal motion across the frame originates from the friction-disk K. Its use in connection with the horizontal and vertical feed when the milling attachment to the ram is being actuated will be explained hereinafter.

Attached to the saddle is a vertical cone-shaft 30, driven by beveled wheels from the 75 horizontal cone-shaft 30^a, and the horizontal cone-shaft is belted to the cone 21^e on the main shaft of the machine. From the cone 30^a a belt passes to a cone 30^c at the front of the saddle, and the shaft of this cone has 80 mounted upon it a movable friction-wheel 30^d, that bears against a face friction-wheel 30^e on a horizontal worm-shaft 30^f. The worm-shaft 30^f actuates a pinion on the shaft 30^g, on the end of which shaft 30^g is a gear-wheel 30^h. This gear-wheel 30^h becomes an actuator to drive the shaft H or the shaft H'. It drives the shaft H' when the large gear 85 hereinafter spoken of engages on the shaft H' and is in mesh with the wheel 30^h. It 90 drives the shaft F, which in turn actuates the screw feed-shaft G. By transferring this large wheel to the shaft H the wheel 30^h becomes an actuator to the shaft H and the shaft H actuates the screw feed-shaft E and 95 drives the traveling nut thereon and raises or lowers the saddle. The feed-wheel 30^d is adjustable vertically along the shaft 30^f, and it carries on a collar connected with it a finger 100 31, which is connected with a sliding sleeve 100 31^a on a graduated indicator-rod 31^b. By shifting the friction-wheel 30^d along the shaft the speed communicated to the worm-shaft 105 30^f can be varied, and thus the relative speed of the driving mechanism and either the vertical feed or the horizontal feed can be regulated, and the indicator-rod 31^b enables the user to set the mechanism at any desired point between the extremes of which the machine is capable.

In the front of the column is a vertical plate 32, provided with T-grooves, by means of which a bearing or a support 32^a is secured to the vertical column, and the cutting-tool in its work draws directly against the column 115 which supports the ram. The bottom fastening and the vertical bearing together secure the work firmly against vibration and prevent the inequality of work due to such vibration. The usefulness of the vertical bearing-plate 32 will be evident if we consider the action of the machine on the work, which must be secured by a small bearing to the surface plate, but which rises high—say six feet high above the surface plate. Such a piece of material to be worked on could not be well secured by its small bearing on the surface plate, and it would not stand the thrust of the cut, but by means of the vertical plate 32 such a piece of material may be supported along 125 one side even to its extreme upper end, and inasmuch as the movement of the cutter is a pulling or draw-cut movement the heavier the cut is the more tightly the material will 130

be held against the vertical bearing-plate, and the thrust is counteracted or taken up directly by the column which supports the ram, and consequently those pieces of material of

5 irregular shape, but which are high in proportion with the extent of base that may be secured to the surface plate, can be as readily operated on and as accurately worked as can the larger piece that may be secured by large 10 bearing-surfaces to the surface plates.

What we claim is—

1. In a traveling-head shaper, the combination of the feed mechanism, a feed-actuating shaft H , or H' , a shaft 30^g , a shaft n , 15 means for imparting a continuous rotary motion to the shaft 30^g , means for imparting an intermittent rotary motion to the shaft n , and means for connecting either the shaft 30^g , or the shaft n , with the feed-actuating shaft, substantially as described.

2. In a traveling-head shaper, the combination of a base, horizontal ways on said base, a column adapted to travel on said ways, vertical ways upon said column, a saddle adapted 25 to slide upon said vertical ways, means for feeding said column and said saddle along their respective ways, a ram adapted to reciprocate in a direction at right angles to the motions of said column and said saddle and 30 to carry the cutting-tool, and means for reciprocating said ram to make the cut, substantially as described.

3. In a traveling-head shaper, a lever, K' , provided with a slot k' , a rotating part K , a 35 radially-adjustable pin upon the part K , extending into the slot k' , and adapted to actuate said lever, a segmental rack upon said lever, and a feed-actuating mechanism gearing with said segmental rack, substantially as described.

4. In a traveling-head shaper, in combination with a ram and a horizontally-movable column by which the ram is carried, a track upon which the column rests in part and is 45 adapted to slide, and a truck upon which the column rests, and is adapted to ride, in part, substantially as described.

5. In a traveling-head shaper, in combination with a ram, and a horizontal movable 50 column by which the ram is carried, a track upon which the column rests in part and is adapted to slide, and a truck upon which the column rests, and is adapted to ride in part, and means for regulating the relative bearing 55 of the column on the truck and the track, substantially as described.

6. In a traveling-head shaper, in combination with a ram, and a column by which the ram is carried, a base supporting a track 60 on which the column rests in part, a truck running on the base and supporting the column in part, and springs arranged between

the truck and the column, whereby the weight of the column is partly carried on the trucks and carried on the track, substantially as described.

7. In a shaper, the combination of a hollow ram, means for reciprocating the ram, an arbor mounted in the ram, a splined shaft parallel with the ram, a train of gear-wheels 70 mounted on said ram adapted to rotate said arbor, and adapted to traverse and to be actuated by said splined shaft, and means for rotating said splined shaft, substantially as described.

8. The combination of a surface plate provided with, T-slots, a bed-plate 20, secured by bolts to said surface plate, a horizontally-movable vertical column supported on said bed-plate, a vertically-movable saddle on said 80 column, a ram adapted to reciprocate in a direction at right angles to the movement of said column and said base, a milling-tool in said ram, means for actuating said milling-tool, and means for feeding the various parts, 85 substantially as described.

9. In a traveling-head shaper, the combination of a base, horizontal ways on said base, a column adapted to travel on said ways, vertical ways upon said column, a saddle adapted 90 to slide upon said vertical ways, and means located upon said saddle for regulating and controlling the feed of said column and saddle, substantially as described.

10. The combination of a T-slotted surface plate, a draw-cut shaper, the supporting-column of the actuating mechanism of said draw-cut shaper being adapted to be attached to said surface plate by bolts passing into said slots, so as to be attachable at will 100 to said surface plate at different positions thereon, a vertical plate on the supporting-column, arranged to have a horizontal support 32^a , secured thereto, whereby the draw of the cutting motion of the shaper, is resisted directly by said supporting-column 105 through said plate and the support 32^a , substantially as described.

11. The combination with a traveling-head shaper with its supports and actuating mechanism, a vertical plate on the face of the supporting-column of said shaper, arranged to have a horizontal support 32^a , secured thereto, whereby the draw of the cutting motion of the shaper, is resisted directly by said supporting-column 115 through said plate and the support 32^a , substantially as described.

In testimony whereof we sign this specification in the presence of two witnesses.

MATTHEW MORTON.
HENRY E. MORTON.
